US00D892809S

(12) **United States Design Patent** (10) Patent No.: **US D892,809 S**
(45) Date of Patent: **** Aug. 11, 2020**

(54) **CONNECTION APPARATUS**

(71) Applicant: **Guangzhou Landscape Communication Equipment Co., Ltd,**
Guangzhou (CN)

(72) Inventor: **Youqing Feng**, Anqing (CN)

(**) Term: **15 Years**

(21) Appl. No.: **29/732,158**

(22) Filed: **Apr. 22, 2020**

(51) LOC (12) Cl. **14-02**

(52) U.S. Cl.

USPC **D14/449**

CLAIM

The ornamental design for a connection apparatus, as shown and described.

DESCRIPTION

FIG. 1 is a first perspective view of a connection apparatus showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.
